ANGLE COAT HOOK

Robert W. Schier, Northfield, and Larry F. Odar, Northbrook, Ill., assignors to Krueger Metal Products, Inc., Green Bay, Wis., a corporation of Wisconsin

Filed Mar. 18, 1968, Ser. No. 11,025

Term of patent 14 years

Int. Cl. D6—01; D8—03

U.S. Cl. D33—8

FIG. 1 is a view in perspective showing an angle coat hook embodying our design.

FIG. 2 is a plan view thereof.

FIG. 3 is a side elevation thereof.

FIG. 4 is a fragmentary bottom plan view of the terminal portion of one of the hooks.

FIG. 5 is a detail view taken in section on the line 5—5 of FIG. 3.

FIG. 6 is a detail view taken in section on the line 6—6 of FIG. 3.

We claim:

The ornamental design for an angle coat hook, as shown.
